UNITED STATES PATENT OFFICE.

EDWARD C. SHORES, OF CHICAGO, ILLINOIS, ASSIGNOR OF SIX-SEVENTHS TO JOHN H. JOHNSON, OF COFFEYVILLE, KANSAS.

VAPOR-FORMING DEVICE FOR INTERNAL-COMBUSTION ENGINES.

1,184,580.

Specification of Letters Patent.

Patented May 23, 1916.

Application filed October 7, 1914. Serial No. 865,533.

To all whom it may concern:

Be it known that I, EDWARD C. SHORES, a citizen of the United States, residing at Chicago, in the county of Cook and State 5 of Illinois, have invented certain new and useful Improvements in Vapor-Forming Devices for Internal-Combustion Engines; and I do hereby declare the following to be a full, clear, and exact description of the 10 invention, such as will enable others skilled in the art to which it appertains to make and use the same.

This invention relates to vapor forming devices for internal combustion engines, and 15 one of the principal objects of the invention is to provide means for converting coal oil or other oils heavier than gasolene into gas and mixing the same with air to be used for charging internal combustion engines.

20 Another object of the invention is to provide means for treating coal oil or other oils heavier than gasolene through a pipe from a tank into the exhaust pipe of the engine to heat the same and to convert the oil into 25 gas, a gasolene starting device being employed to give the additional impetus to the engine and to be then cut off after the oil has been sufficiently heated in the exhaust pipe to be converted into gas.

30 These and other objects may be attained by means of the construction illustrated in the accompanying drawings, in which,

Figure 1 is a diagrammatic view showing the exhaust pipe in section and illustrating 35 the manner of treating the coal oil to be converted into a gas, Fig. 2 is a vertical sectional view of the gas pipe and carbureter, Fig. 3 is a detail sectional view of the coal oil float, Fig. 4 is a detail plan view of 40 the upper end of the air inlet of the carbureter, and Fig. 5 is a detail view showing the manner of connecting the gasolene stocking pipe to the dashboard of the vehicle.

Referring to the drawings, which show 45 the invention connected to parts of a four cylinder internal combustion engine adapted to be used on motor vehicles, the numeral 1 designates a gasolene tank of small size. A gasolene pipe 2 extends from the tank 1, 50 and is connected to the dashboard 3 by extending from the underside through the same and back again, at which point a needle valve 4 is provided. From this point the gasolene pipe 2 extends to the up- 55 per part of the carbureter 5. This arrange-

ment is used for the purpose of starting the engine preparatory to the use of coal oil as a fuel.

The coal oil tank 6 is provided with a discharge pipe 7 which leads to a float 8 60 comprising a casing having a float regulator 9 therein. From the float the discharge pipe 10 leads into the exhaust pipe 11 at the point 12 adjacent the muffler. The pipe 10 contains the coal oil up to substantially the 65 point 13 and this level of coal oil is regulated by the float. When the oil in the pipe 10 is sufficiently heated to convert the gasolene into gas it is led from the point 13 up and out the exhaust pipe 11 at the point 15 70 where the pipe 10 goes up into another pipe or gooseneck 14 which fits over it in such a manner as to let a little of the gas escape in case of excess pressure. This pipe or gooseneck 14 is wrapped with asbestos 16 so 75 that it will hold the heat and conduct the gas to the carbureter 5.

The carbureter 5 is provided with a cup or bowl 18 to catch any of the coal oil which has not been converted into gas and this 80 bowl is provided with a lip cock 19. The air enters the mixer through the opening 20 which surrounds a spider 21 seated in the end of the air inlet, and a valve 22 provided with a stem 23 extending through the spider is seated in a flaring valve seat 24 and adjusted relatively to the seat to regulate 85 the supply of air by means of the threaded valve stem 25 extending through the casing and provided with a hand wheel 26. The 90 mixer is provided with a discharge branch 27, in which is seated the throttle valve 28 and said branch at its upper end is provided with branches 29 which lead to the engine cylinder. Other heavier oils may be 95 used in the same way as coal oil, but they are not quite as reliable as coil oil. The exhaust enters the four points 30.

The operation of the invention may be briefly described as follows: In starting the 100 engine, the valve 4 is opened and a supply of gasolene is led from the tank 1 to the carbureter 5 for initially starting the engine. After a few revolutions or impulses of the 105 engine, the exhaust pipe 11 is heated sufficiently to convert the coal oil in the pipe 10 into a gaseous fuel. This gaseous fuel is led from the point 13 through the gooseneck 14 and into the mixer where it is mixed with air and led to the engine. 110

From the foregoing it will be obvious that an apparatus made in accordance with this invention will utilize coal oil as a fuel for internal combustion engines, thus cheapening the cost of running the engine, and at the same time providing a reliable and efficient fuel which is more reliable and less dangerous than the ordinary gasoline.

Various changes may be made in the details of construction without departing from the spirit and scope of the invention as defined in the claims.

What is claimed is:—

1. A vaporizing device for internal combustion engines comprising a carbureter and a tank, an air mixer formed on said carbureter, an air supply valve mounted in said air mixer, means for regulating said valve, a cup formed on the lower extremity 15 of the carbureter and provided with a drain cock thereon, a gasolene pipe leading from the tank and connected to the upper end of said carbureter, a goose neck pipe connected to the carbureter adjacent the cup and terminating adjacent the exhaust pipe of an engine, an oil pipe adapted to lead through

the exhaust pipe of an engine and connected with said goose neck pipe, and means for regulating the flow of oil within said oil pipe.

2. A vaporizing device for internal combustion engines comprising a carbureter, an air mixer formed on said carbureter, a gasolene pipe connected to said carbureter, a goose neck pipe connected to the carbureter and terminating adjacent the exhaust pipe of an engine, an oil pipe leading from an oil tank adapted to enter the exhaust pipe of an engine adjacent the outlet end and exit adjacent the inlet port and connected to said goose neck pipe, a float regulator connected to said oil pipe to control the level of oil within the oil pipe, and means for allowing the excess pressure of gas within the oil pipe to escape.

In testimony whereof I affix my signature in presence of two witnesses.

EDWARD C. SHORES.
